[57] CLAIM

The ornamental design for a wallplate, as shown and described.

DESCRIPTION

FIG. 1 is a front elevational view of a wallplate showing our new design;

FIG. 2 is a right side elevational view thereof, the left side being a mirror image;

FIG. 3 is a rear elevational view thereof;

FIG. 4 is a sectional view taken in the direction of the arrows on line 4—4 of FIG. 1;

FIG. 5 is a top plan view thereof, the bottom being identical;

FIG. 6 is a sectional view taken in the direction of the arrows on line 6—6 of FIG. 1;

FIG. 7 is a front elevational view of the second embodiment of the design of FIG. 1, the only difference being the curved groove over the upper mounting hole; and, FIG. 8 is a front elevational view of the third embodiment of the design of FIG. 1, the only difference being the straight groove over the upper mounting hole.

The characteristic feature of the design resides in the particular pattern created by the grooves in the surface of the wallplate.
